ELECTRICAL CONNECTOR PLUG

Orrin H. Thomas, Williamsport, Pa.

Application May 24, 1956, Serial No. 41,626

Term of patent 3½ years

(Cl. D26—1)

I claim:

The ornamental design for an electrical connector plug, as shown.
